UNITED STATES PATENT OFFICE.

JOHN A. STOOPS, OF CHICORA, PENNSYLVANIA.

METALLIC RAILWAY-TIE AND RAIL-FASTENING.

No. 895,908.

Specification of Letters Patent.

Patented Aug. 11, 1908.

Application filed April 14, 1908. Serial No. 427,037.

To all whom it may concern:

Be it known that I, JOHN A. STOOPS, of Chicora, Butler county, Pennsylvania, have invented a new and useful Metallic Railway-Tie and Rail-Fastening, of which the following is a full, clear, and exact description, reference being had to the accompanying drawings, forming part of this specification, in which—

10 Figure 1 is a perspective view showing a portion of a railway track constructed of my improved ties; Fig. 2 is a side view of the same showing the ties in end elevation; Fig. 3 is a similar view showing a modification of the fastening; Fig. 4 is a sectional view on the line IV—IV of Fig. 2; Fig. 5 is a plan view showing the fastening as in Fig. 3; Fig. 6 is a detail sectional view showing a modification in the form of the tie; and Fig. 7 is a 20 perspective view of the adjustable clip or lug.

My invention has relation to metallic railway ties and fastenings therefor, and is designed to provide a tie which shall have a 25 bearing in the ballast of the road-bed in such a manner as to prevent creeping of the tie either longitudinally or endwise; which can be furnished at a comparatively low cost; which will possess the requisite amount of 30 resiliency; and to which the rails may be easily and securely fastened.

The precise nature of my invention will be best understood by reference to the accompanying drawings, which will now be described, it being premised, however, that various changes may be made in the details of construction by those skilled in the art without departing from my invention as defined in the appended claims.

40 In accordance with my invention I construct each tie of two lengths or sections 2 of pipe or tubing, each of the length of an ordinary tie. The end portions of these sections of pipe or tubing are abutted side by side, being preferably flattened at their abutting portions as indicated at 3 and secured to each other by bolts 3^a or other suitable means. The intermediate portions between the rails are separated from each other to form an 50 opening 4 between them.

The track rails 5 are seated upon plates 6 which rest upon the upper surfaces of the ties, having preferably concaved seats 7 to fit the convex surfaces of the ties. These plates 55 are also preferably formed with longitudinal grooves or depressions 8, in which the rail

bases are seated, and in which the rails are secured by means of spike-headed bolts 9. These bolts 9 have ordinary spike heads and extend through the plates 6 being secured at the under sides thereof by the nuts 10. The rails are also further held by means of the clips or lugs 11, which are bolted or otherwise secured to the plates, slotted bolt holes 11^a being provided to permit adjustment. 65 One or more of these clips or lugs may be provided for each plate, and any desired number of the spikes may be employed at each tie.

In the form of my invention shown in 70 Figs. 1, 2 and 4, the plates 6 are secured to the ties by means of the U-bolts 12 which extend around underneath the ties, and whose upper ends are secured by the nuts 13. The U-bolts also engage the convex washers 14, 75 which are placed at the under side of the tie and which are preferably grooved to receive these bolts. Instead of using U-bolts I may, however, use ordinary straight bolts as shown in Figs. 3 and 5.

It will be obvious that any suitable stop means may be secured to the end portions of the ties, if desired, for the purpose of assisting the bolts in holding the tie-seating plates 80 from endwise movement on the ties.

By reason of the separation of the two members of which these ties are composed at their intermediate portions, the ballast is allowed to extend upwardly not only between adjacent ties but between the members of 90 each tie, thereby securely holding them from creeping either endwise or longitudinally of the track. The hollow form of the sections of which the ties are composed not only reduces their weight and the amount of metal 95 required for their construction, but it also gives the ties an element of resiliency which is of advantage.

What I claim is:—

1. A metallic railway tie composed of two 100 hollow sections having their end portions abutted and their central portions spread from each other; substantially as described.
2. A metallic railway tie composed of two pipe sections having flattened abutted end 105 portions and separated intermediate portions; substantially as described.
3. A rail tie composed of two hollow pipe sections or members which are separated from each other between the track rails, but 110 whose end portions extending underneath and outside of the track rails are abutted and

secured to each other; substantially as described.

4. The combination with a rail tie composed of adjacent hollow pipe sections, of a rail fastening consisting of a plate seated on the ties and having a longitudinal groove or seat for the base flanges of the rail, holding devices carried by said plate for engaging the rail, and bolts securing the plates to the ties; substantially as described.

5. The combination with a railway tie, consisting of two hollow pipe sections having

abutted end portions, of a rail-seating plate seated upon said ties and fitted thereto, bolts securing said plates to the ties, and rail-engaging means carried by said plates, arranged to engage the base flange of the rail; substantially as described.

In testimony whereof, I have hereunto set my hand.

JOHN A. STOOPS.
